UNITED STATES PATENT OFFICE.

JOHN WALKER FLAVELL SOLE AND ALBERT FRED FARLEY, OF GUELPH, ONTARIO, AND JOSEPH FRANCIS MACKLE, OF WESTMOUNT, QUEBEC, CANADA.

RAILWAY-CAR COUPLING.

No. 902,616.

Specification of Letters Patent.

Patented Nov. 3, 1908.

Application filed November 15, 1907. Serial No. 402,843.

To all whom it may concern:

Be it known that we, JOHN WALKER FLAVELL SOLE, mechanic, of the city of Guelph, in the Province of Ontario, Canada; ALBERT FRED FARLEY, stationary engineer, of the said city of Guelph, and JOSEPH FRANCIS MACKLE, railway employee, of Westmount, in the county of Hochelaga, Province of Quebec, Canada, have invented certain new and useful Improvements in Railway-Car Couplers, of which the following is a specification.

The object of our invention is to devise a coupler (1) of great strength and durability to meet the strains due to the constantly increasing loads of the modern railway, (2) that will readily couple and uncouple on a curve, and will have more or less flexibility, which tends to reduce strain upon the parts, (3) that is perfectly automatic, always remains ready for coupling after uncoupling, and is convenient for operation by the train hands. We attain our objects by employing a solid draw head on the exterior of which the knuckle and guard are pivoted. The pin which locks the rear end of the wings of the knuckle engages the latter in such a way that although the knuckle is permitted to close readily when two draw heads contact yet it will be effectually held open against accidental closure. The pin in the act of uncoupling is automatically held up until the two couplings have completely disengaged, and any trouble due to irregular shunting, by which the draw heads are partly disengaged and again reengaged, is avoided. The guard having a limited outward swing may move to give a sufficiently wide mouth to the coupling to enable it to readily engage and disengage on a curve.

Figure 1 is a plan view of our improved coupler in the locked position. Fig. 2 is a similar view with the coupler wide open. Fig. 3 is an elevation, looking in the direction of the line *a—a* in Fig. 1. Fig. 4 is a similar view looking in the direction of the line *a—a* in Fig. 2. Fig. 5 is a sectional detail showing more particularly the locking pin and its retaining piece. Fig. 6 is a perspective view showing the draw-head, knuckle and guard separated.

In the drawings like letters of reference indicate corresponding parts in the different figures.

G is the draw head, which is substantially

solid in construction. On this draw head is hinged the knuckle A, which is provided at top and bottom with the wings I, which are journaled upon the draw head by means of the pin B.

The draw head, it will be noted, is suitably cut out above and below to receive these wings. To the opposite side of the draw head is hinged the guard C, which is formed as a knuckle provided with wings J, pivoted on the draw head by means of a pin D. The draw head is suitably cut out at top and bottom to receive these wings.

The outward swing of the guard is limited by the shoulders *a* formed on the wings J, adapted to engage shoulders *b* formed on the draw head. Its inward swing is limited by the ends of the wings J coming in contact with the portions of the draw head forming the back of the rabbet cut out to receive the wings J. This construction of the guard is intended to facilitate the coupling of cars on a curve, as the guard may readily swing outwardly to a limited extent to provide greater flare to the mouth of the coupling, as shown in Fig. 2.

E is a locking pin, which is formed as a rectangular bar having notches or recesses *c* cut out to allow the rear ends of the wings of the knuckle A to swing outward and inward past the pin in the acts of coupling and uncoupling.

When the draw head is in the coupled position the ends of the wings bear against the solid portions of the pin and the coupler is effectively locked.

A projecting lug *d*, with a wedge shaped back, is formed on the pin E. This lug by contacting with the top of the draw head beside the pin serves to limit the downward drop of the pin.

F is a retaining piece, which is provided with an opening through which the pin E loosely passes. A hinge pin *g* is provided for this retaining piece, which is secured to the lugs *e* formed at each side of the retaining piece. This hinge pin *g* is fitted into a notch *h* formed in the side of the projection *f* adjacent to the pin E. The pin thus forms a closure for the notch, and effectively retains the hinge pin in position.

It will be noted that the under edge of the forward side of the retaining piece F is beveled upwardly and outwardly.

The rear end of the upper wing I is provided with an upward projection *i*, which is adapted to engage the under side of the forward end of the retaining piece to raise the latter under the conditions hereinafter described. A projection *m* on the outside of the locking pin E prevents the retaining piece F from being raised over the top of the pin.

10 It will also be noted that the rear end *j* of each of the wings I is wedge shaped, the inclination being inwardly and upwardly. (See Figs. 5 and 6.)

15 The upper side of each of the notches *c* is similarly shaped. Hence when the knuckle is open it cannot be closed unless the pin be lifted by the action of the wedges to allow the ends of the wings to pass.

20 As the pin will weigh approximately twelve pounds its weight will be sufficient to prevent such a movement of the knuckle taking place accidentally, and the coupler will remain in the uncoupled position until properly engaged by the coupler on another car.

25 The operation of our improved coupler is substantially as follows; to uncouple all that is necessary is to raise the pin E until the retaining piece falls beneath the projection *d* on the side of the pin. The retaining 30 piece will securely hold the pin in this position until the knuckle A opens sufficiently to bring the projection *i* beneath the forward side of the retaining piece F, thus lifting it and releasing the pin, which drops until the 35 upper edges of the notches *c* engage the wedge shaped ends of the wings I. In this condition the coupler is in position to automatically re-couple without further attention. To couple requires no attention on 40 the part of the operator being perfectly automatic.

The incoming coupler engages the open knuckle A and closes it. The locking pin E immediately drops and locks back the wings 45 I thus holding the knuckle closed. The end of the knuckle A of the incoming coupler engages the wings J of the guard C so that the latter is retained in the position shown in Fig. 1.

50 When making up trains or shunting, if it is desired to shunt off down a siding, the operator standing at the side of the car lifts the pin D by means of the mechanism usually employed for that purpose, and the pin remains lifted until the car has been thrown off and the knuckle entirely swung out.

55 If, through unsteady pushing of the driver, or for any other reason, the knuckle is partly opened out and closed again no effect is produced on the pin, which remains lifted and is not released until the knuckle has swung entirely open. The position of the knuckle A at which the pin drops can be regulated by changing the position of the projection *i* so that if desired the pin may be allowed to drop

before the knuckle is entirely open. The important point is to so place it in relation to the retaining piece F that no partial separation of the couplers shall lift the retaining piece so that when the couplers come together again the pin re-drops to the locking position.

In shunting couplers are often subjected to great strain from jerking, twisting or jamming together. As our draw head is substantially solid, and as the wings of the knuckle and the guard, being on the outside, may be made as large and strong as is necessary our device may be made much stronger than when the hollow construction of the draw head is employed.

What we claim as our invention is:

1. In a car coupler the combination in a solid draw head provided with a guard, of a knuckle exteriorly pivoted on the draw head 85 and adapted to swing outward to an uncoupled position and means for automatically locking said knuckle exterior to the draw head at top and bottom when the knuckle has been swung into the coupled position. 90

2. In a car coupler the combination of a solid draw head, a knuckle exteriorly pivoted on the draw head, and provided with wings extending inwardly of the pivot, the upper and lower surfaces of the draw head being 95 raised back of the path in which the wings swing, and a locking pin vertically movable in a hole in the draw head and projecting partly from the faces of the raised portions of the draw head into the path of the wings. 100

3. In a car coupler the combination of a draw head; a knuckle pivoted thereon and provided with a wing extending inwardly of the pivot; a vertically movable locking pin notched for the passage of the wing; a retaining piece pivoted adjacent to the pin; and a projection on the pin adapted to raise and pass the retaining piece and engage its upper surface, the inner end of the wing of the knuckle being adapted as the knuckle swings 110 open to engage and release the retaining piece.

4. In a car coupler the combination of a draw head; a knuckle pivoted thereon and provided with a wing extending inwardly of the pivot; a vertically movable locking pin notched for the passage of the wing; a retaining piece through which the locking pin loosely passes; a pivot pin for the retaining piece at one side of the locking pin below its 115 upper surface and pivoted in the draw head; and a projection on the locking pin adapted to raise and pass the retaining piece and engage its upper surface, the inner end of the wing of the knuckle being adapted as the knuckle swings open to engage and release the retaining piece. 120

5. In a car coupler the combination of a draw head; a knuckle pivoted thereon and provided with a wing extending inwardly of 130

the pivot; a vertically movable locking pin
notched for the passage of the wing; a retaining
piece through which the locking pin
loosely passes; a pivot pin for the retaining
5 piece at one side of the locking pin below its
upper surface and pivoted in a notch formed
in the draw head opening into the cavity for
the locking pin which serves to retain the
pivot pin in place; and a projection on the
10 locking pin adapted to raise and pass the re-
taining piece and engage its upper surface,
the inner end of the wing of the knuckle be-
ing adapted as the knuckle swings open to en-
gage and release the retaining piece.
